UNITED STATES PATENT OFFICE.

BENJAMIN HARRIS, OF EAST AKRON, OHIO, ASSIGNOR OF TWENTY-FOUR PER CENT.
TO MICHAEL LURIE AND TWENTY-FIVE PER CENT. TO EDWARD LURIE.

MOTOR-METER.

1,380,955.

Specification of Letters Patent. Patented June 7, 1921.

Application filed February 2, 1920. Serial No. 355,613.

To all whom it may concern:

Be it known that I, BENJAMIN HARRIS, a citizen of the United States, residing at East Akron, in the county of Summit, and State of Ohio, have invented new and useful Improvements in Motor-Meters, of which the following is a specification.

This invention relates to motor meters, which embodies among other features a rotatable element having indicia relative to the temperature of the motor, thermostatic means being employed for rotating the element to present the indicia to view.

Another important object of the invention resides in the provision of a valve controlled exhaust port which is automatically uncovered when the rotatable element reaches a predetermined point to permit of the exhaust of steam from the radiator.

The nature and advantages of the invention will be better understood when the following detailed description is read in connection with the accompanying drawings, the invention residing in the construction, combination and arrangement of parts as claimed.

In the drawings forming part of the specification like numerals of reference indicate similar parts in the several views and where-

30 in:

Figure 1 is a view in elevation of the meter constructed in accordance with my invention.

Fig. 2 is a vertical sectional view there-

35 through.

Fig. 3 is a horizontal sectional view.

Fig. 4 is a detail view of the rotatable ele-

ment.

Fig. 5 is a vertical sectional view taken 40 through a modified form of the invention.

Fig. 6 is a horizontal sectional view there-

through.

Fig. 7 is a detail view of a modified form

of valve for the exhaust pipe.

45 Referring to the drawings, in detail, 10 in-

dicates a radiator cap of usual construction provided with a central opening to receive a reduced portion 11 of a receptacle having an enlarged upper portion 12, preferably of

50 spherical formation to receive the rotatable element 13. The element in the preferred

form of the invention is in the nature of a

drum which is secured upon a vertically dis-

posed shaft 14 having its opposite end jour-

55 naled in bearings 15. The drum 13 is open

at both ends, and provided with horizontally disposed arms 16, for supporting the drum upon the shaft 14. The drum 13 is provided with vertically disposed rows of letters 17, which are stamped from the material forming the drum, these letters being arranged in any combination to convey information as to the temperature of the motor. The upper part of the receptacle, or casing 12 is provided with a sight opening 18 of an elongated nature, and of such size that but one row of letters can be presented to view at a time.

Depending from the top of the receptacle or casing 12 and passing through the drum 13 is a radiant tube 19. This tube is disposed adjacent the sight opening 18 to illuminate the particular row of letters presented to view at night time. If desired, a reflector 20 can be supported by the tube in any suitable manner.

The reduced lower portion 11 which enters the cap 10 of the radiator has arranged therein, thermostatic devices, in the nature of coiled springs 21. These springs are made out of suitable material, to be effected by heat, and expand and contract with a variance of temperature. The springs are terminally connected to the shaft 14 and to the adjacent parts of the casing 11 and obviously impart rotation to the shaft 14 upon the contraction and expansion of the same. Tubes 22 are passed through the lower portion of the receptacle over the springs 21, heat or water circulating through these tubes and confining the springs 21 in a place in which they will be affected by the temperature of the water in the radiator. The row of letters indicated at 23 on the rotatable element 13, is covered with a red glass to indicate danger, and when this row of letters is presented to view through the sight opening 18, the steam in the radiator is automatically exhausted in a manner to be presently described.

For this purpose the lower portion 11 of the casing or receptacle is provided with an exhaust port 24 normally closed by means of a valve 25. The valve has a tail portion projecting within the receptacle and in the path of movement of a finger 26 radiating from the shaft 14.

The construction and arrangement of parts is such, that when the rotatable element 13 is actuated to present the row 23 of

100

105

110

letters to view through the opening 18, indicating danger the finger 26 assumes a position to engage the tail portion of the valve, thereby opening the latter to exhaust the steam from the radiator through the pipe 27. The pipe 27 communicates with the port 24 and opens at its opposite end to the atmosphere through the top of the receptacle 12. In the modified form of the invention the springs, or in other words the thermostatic devices 30, are associated with a horizontally disposed shaft 31 journaled in the lower portion of the receptacle 32. The shaft 31 is provided with a crank 33 which is connected by one end of an operating shaft 34. The opposite end of the shaft 34 is connected to the crank portion 35 of a horizontally disposed shaft 36 journaled in suitable bearings 37 carried by the receptacle 32. A disk 38 is carried by each end 36 for rotation therewith, and each disk is provided with a plurality of radially disposed rows of letters which are preferably stamped from the disk, the letters being combined to convey certain information relative to the temperature of the motor. In other words, the disks 38 are utilized for the same purpose as the element 13 hereinabove described in connection with the preferred form of the invention. The radiant tube 39 depends from the top of the receptacle 32 and is positioned between the disks 38, so that the indicia thereon can be readily viewed at night. Both the front and back of the casing 32 is provided with an elongated sight opening 40, so that the meter can be read from either the front or back of the same. It is of course understood each disk 38 carries the same indicia arranged in the same manner. When the thermostatic devices 30 are expanded or contracted by the variation of temperature, the shaft 31 is rotated obviously imparting a similar movement to the shaft 36 through the instrumentality of the connecting rod 34. In this manner the disks 38 are rotated to present to view through the sight openings 40 information relative to the temperature of the motor. This form of the invention is the same as that described in connection with the preferred form of the invention.

In Fig. 7 I have disclosed a modified form of valve or in other words a modified form of mechanism for controlling the valve of the exhaust pipe which is here indicated at 45. Arranged within this pipe is a butterfly valve 46 the axis 47 of which is terminally connected with a right angularly shaped arm at the point of juncture between the branches 48 and 49 thereof. Each of these branches has its extremity offset, the said extremities being arranged in paral-

lism and each being provided with a roller 50. Carried by the reciprocating shaft 34 is a substantially U-shaped member 51 the latter being equipped with a roller 52 adapted to alternately engage the roller 50 of the right angularly shaped arm in order to control the movements of the valve 46. The roller 52 operates between the rollers 49, and when brought into engagement with one of the rollers, upon movement of the shaft 34 in one direction, it operates the valve 46 to open the latter. Upon reverse movement of the shaft 34, the roller 52 is brought into engagement with the other roller 50 which now assumes an uppermost position, so as to close the valve 46 as will be readily understood.

While it is believed that from the foregoing description, the nature and advantages of the invention will be readily apparent, I desire to have it understood that I do not limit myself in this connection and that such changes may be resorted to when desired as fall within the scope of what is claimed.

Having thus described my invention I claim:

1. A motor meter comprising a casing having a sight opening, a rotatable element arranged within the casing and having indicia thereon, means for rotating said element, and a valve controlled exhaust port normally closed by said valve and adapted to be uncovered at a predetermined temperature, and means for automatically operating said valve to uncover said port.

2. A motor meter comprising a casing having a sight opening, a rotatable element arranged within the casing and having indicia thereon, thermostatic means for rotating said element, said casing having a steam exhaust port, a pipe arranged within the casing and leading from said port to the atmosphere, a valve normally closing said port, and means controlled by said element for automatically operating said valve to uncover the port when said element reaches a predetermined position.

3. A motor meter comprising a casing having a sight opening, a rotatable element arranged within the casing and having indicia thereon adapted to register with said opening, thermostatic means for rotating said element, said casing having a steam exhaust port, a pipe arranged within the casing and leading from said port to the atmosphere, a valve normally closing said port, and means carried by said rotatable element for automatically operating said valve to uncover the port when said element reaches a predetermined position.

In testimony whereof I affix my signature.

BENJAMIN HARRIS.
